Attorney

UNITED STATES PATENT OFFICE.

OTTO THIEME, OF HARTFORD, CONNECTICUT, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed September 7, 1922. Serial No. 586,585.

To all whom it may concern:

Be it known that I, OTTO THIEME, a citizen of the United States, residing in Hartford, in the county of Hartford and State of Connecticut, have invented certain new and useful Improvements in Combined Typewriting and Computing Machines, of which the following is a specification.

This invention relates to a combined typewriting and computing machine of the general type shown in United States patent to G. O. Degener, No. 1,271,290, dated July 2, 1918, in which a typewriting and a computing action may be carried on concomitantly under the control of a single set of numeral keys.

In this general type of machine, the numeral keys when actuated operate type actions to print numbers, and, at the same time, enable the setting of index pins in a valuating mechanism to determine the extent of rotation of computing wheels of one or more computing heads, by a source of power, to correspond with the particular numeral keys struck. The numeral keys are used to select the particular pins to be set, and are connected to bring into play automatic power-actuated mechanism for performing the actual work of setting the pins, and thus relieving the numeral keys of this burden. By this means also, the numeral keys can be freely actuated without actually setting the index pins unless the source of power mentioned is brought into play.

The effectiveness of the numeral keys to set in motion the computing mechanism, is governed by the shifting between effective and ineffective positions of a light tripper, which is universally actuatable by all of the numeral keys. This tripper is controlled from the carriage as to its effective and ineffective positions, to correspond with non-computing portions of the travel of the typewriter carriage and with computing zones in the travel of the typewriter carriage. This tripper controls the bringing into play of the source of power, so that when the tripper is in its ineffective position, the source of power cannot be rendered effective to set the pins, and, hence, the numeral keys may be actuated to typewrite without bringing the computing mechanism into play. The

effectiveness of the tripper while governed from the carriage by automatic mechanism acting to determine computing zones, may be silenced or rendered effective at will by manual controlling means.

A lock is also used to prevent the actuation of a numeral key in digit or denominational columns corresponding to the writing of other characters than numbers. This is more especially applied to the denominational columns corresponding to the decimal point, the space between hundreds and thousands, thousands and millions, etc. This lock, as shown in the aforesaid patent, is preferably operable at other times for various safeguarding purposes.

In the patent referred to, the numeral keys are locked by a blocking device movable into the common path of movement of a set of arms, one connected to each numeral key. The blocking device is in the form of an arm actuatable by a collar or stop on a shiftable rod, in turn actuated by a shifter or plunger connected to what is therein termed a zone-controller, and which carries certain cams co-operating with a tappet on the platen carriage. The same shift rod, which operates the key-blocking device, also serves upon a lesser movement thereof, to set the tripper for the motor drive of the computing mechanism; and this movement of the shift rod is determined by one of the cams on the zone-controller. The mechanism just referred to is more particularly shown in Figure 7 of the aforesaid patent.

An object of the present invention is the provision of means whereby the adjustable column or computing zone stops, on the stop-bar of the platen carriage, may be used to control the operations, aforesaid, of the numeral-key-locking means, and of the drive of the computing mechanism. Otherwise expressed, an object of the invention is the combination in one, simple, durable and unitary structure, positionable at will, and with a minimum of trouble, at any desired computing zone position on the platen carriage, of a column stop and cams for effecting the aforesaid operations.

A further object of the invention is the provision of means whereby the same column stop may be utilized as the pick-up dog for a pick-up device, such, for instance,

as shown in United States patent to W. Wright, No. 1,244,398, dated October 23, 1917, for causing the carriage for the movable element of the computing mechanism 5 to have its step-by-step movement with the platen carriage from column position of higher denomination to column position of lower denomination. It may be the computing head which is moved by this pick-up carriage with respect to the master wheel, as in the aforesaid patent; or it may be the master wheel which is moved thereby with respect to the computing head.

Further objects of the invention are the 15 provision of means for automatically locking the numeral keys against operation except when use of the same in a computing zone is desired; and the provision of means whereby, after the numeral keys have been 20 thus automatically locked, the same may nevertheless be unlocked to permit use of the same in writing between computing zone positions, or in writing when the computing 25 mechanism is disconnected.

25 A feature of the invention is the use, for such unlocking of the keys, of a device, such, for instance, as shown in the aforesaid patent, for disabling the computing mechanism to permit use of the typewriting machine in 30 the ordinary way.

Other features of the invention are the use of the same above-mentioned unitary column-stop and cam device as the means for locking the keys between computing zone 35 positions; and the use, of such device, as the means for locking down the aforesaid shifter or follower, out of the path of the cams on that device, to prevent vibration and rattling of the shifter and its connections by the cams during return movement 40 of the carriage, with the cams, through the computing zones.

Another feature of the invention is the 45 provision of a simple, effective and reliable automatic lock for the key-locking and tripper connections, and means, also fixable to the unitary stop and cam device, for automatically releasing such lock upon arrival 50 of the platen carriage at position for computing.

Other features and advantages will hereinafter appear.

In the accompanying drawings.

55 Figure 1 is a skeleton perspective, showing the connections by which the tripper is controlled by the column-stops on the type-writer-carriage, and showing a numeral-key and its connections to the draw-rod, through which it acts on the pin-setting motor-controlled mechanisms.

60 Figure 2 is a view, in rear elevation, of the cam-device on one of the column-stops on the column-stop-bar, and the mechanism immediately co-operating therewith for action on the tripper.

Figure 3 is a view, in side elevation, looking from the right, of the mechanism shown in Figure 2.

Figure 4 is a top plan view of the parts shown in Figures 2 and 3.

70 Figure 5 is a view, in rear elevation, showing the action of the cam-device on the column-stop for holding the tripper-connections inactive, with the numeral-keys inoperative, after passage through a computing zone.

75 Figure 6 is a view in perspective of the column-stop and attached cam-plate viewed from the front, and showing the pick-up 80 hook for the computing-head-carriage in operative relation with respect thereto.

85 The parts as shown in the drawings are designed for application to an Underwood typewriting machine. The tripper which controls the key-locking mechanism and other parts, and the key-locking mechanism and other parts controlled by the tripp. may, as stated, be of the style shown in United States patent to G. O. Degener, No. 1,271,- 90 290, dated July 2, 1918, to which reference is hereby made for a more complete exposition of such parts. The computing mechanism itself is not shown, because it is old and well understood. It may be of the character shown in the Degener patent, just referred to, in which the computing head has letter-feed movement to bring one after another of the number-wheels thereof into registration with the master-wheel; or it may be that shown in United States patent 95 to Degener, No. 1,294,425, dated February 18, 1919, in which the computing head is stationary, and in which provision is made for a step-by-step movement of the master-wheel therethrough from one to another of the number-wheels. Whether it be the computing head or the master-wheel which is 100 movable, a carriage is provided for the movable part, such as shown in either of the Degener patents, referred to, and a pick-up 105 connection is provided from such carriage to the platen-carriage of the typewriting machine. The connections of the carriage for such movable element of the computing mechanism, to the platen-carriage, and the 110 manner of operation of the same may, as stated, be as shown in United States patent to W. Wright, No. 1,244,398, dated October 23, 1917, to which reference is hereby also 115 made for a more complete exposition of the purpose and application of the present invention. In the following description, the parts shown in the drawings of the present application, and corresponding to the parts 120 shown in the drawings of the patents, above referred to, will be lettered as lettered in the drawings of such patents where practicable.

125 The carriage of the typewriting machine (not shown) is provided with the usual 130

column-stop-bar or rack 10. One or more column-stops 10^a are adapted to be set at selected column-positions or computing zones along the stop-bar. The stop 5 10^a has two jaws 11 and 12. The jaw 11 is serrated to have a plurality of teeth 13 adapted to be interlocked with the teeth 14 of the rack. The jaw 12 is hinged at 16 to the jaw 11, and a coil-spring 17 acts to 10 cause the jaw 12 to close on the bar, while permitting the jaw 12 to yield in the placement and removal of the stop from the bar. A detent 18 on the jaw 12 snaps over the 15 front edge of the bar to hold the stop to the bar when the stop is thrust into home-position on the latter.

Fast, as by means of screws to the stop 10^a, is a cam-plate 19, having a cam 21, formed on the left-hand end (Figure 2) 20 thereof, for co-operation with a roller 22, set into the upper end of a head-piece 23 on the end of a plunger 220. The plunger 220 is pivotally supported at 25 to a rocker 26, pivoted at 27 to a plate or bracket 28. The 25 plate or bracket 28 is conveniently carried on the rear wall of the casing or stand 30, in which the usual denominational stops 31 have selective movement up and down for co-operation with a tooth 32 on the under 30 face of the jaw 11 of the column-stop. Posts 33 serve to space the plate or bracket 28 from the casing 30, and screws 34, passing through the plate 28 and through the posts 33, thread into the casing 30, to hold the 35 plate 28 in position. To define the extreme up and down positions of the plunger 220, and to hold the rocker 26 for movement parallel to the plate 28, the rocker has an arcuate slot 35 therein, to receive a headed screw 36, which passes, from the rear, through the slot and through a spacing-post 37, set between the rocker and the plate 28, finally to thread into the plate 28.

The plunger 220 is pivotally connected at 38 to one arm 39 of a lever pivoted at 40. The other arm 41 of this lever is provided with a plate 42, forked or bifurcated at 43, to receive a pin 44, carried by an arm 221 on a rock-shaft 222. The pin 44 projects 45 entirely through the slot 43, and, at its rear, has attached thereto one end of a spring 45, the other end of which spring is attached to a pin 46 on the lever-arm 41. The spring 45, by holding the pin 44 in the slot 43, causes the arm 221 to follow the up and down movements of the lever to which the plunger 220 is connected. When, therefore, the cam 21 depresses the plunger, to swing 50 up the lever-arm 41, the arm 221 is also swung up. This movement of the arm 221 draws down a link 224 to depress a lever 225, against the action of a spring 226. The lever 225 is provided with a toe 227, arranged to engage a pin 228 on a segment 55 229. The segment 229 meshes with a cor-

responding segment 230, pivoted on a shaft 231. The segment 229 is connected, by means of a spring 234, to a lever 232, mounted on the same pivot 233 as is the lever 225 and the segment 229. The segments 229 and 230 may be rotated by a finger-piece 235 from the position shown in Figure 1 to a position in which the spring 234 lies to the other side of the lever 232, and back again (as more fully illustrated in Figures 7 and 8 of the Degener Patent No. 1,271,290, above referred to), the movements of the segments being limited in both directions by enlarged teeth on one or both of them at the ends thereof. The spring 234, in either position, tends to draw the lower part of the lever 232 and segment 229 toward each other, so as to rock the lever 232 with respect to the segment. In the position shown in Figure 1, this is prevented by the spring 226, which is stronger than the spring 234, and causes a pin 236 to hold up an arm 237, secured to the lever 232, and forming a part thereof. Another arm 238 of the lever 232 is bifurcated at its upper end to engage the opposite sides of the pivot 231 of the segment 230, and thus to limit the back and forth swing of the lever 232.

When the parts are in the position shown in Figure 1, the actuation of the plunger or shifter 220 by the cam 21 on the stop depresses the lever 225 against the tension of the spring 226, permitting the spring 234 to act, so that the lower end of the lever 232 will be drawn to the left, thereby pulling 100 on a link 239. This link is connected to rock a lever 240, which, in turn, pushes on a link 241, connected to rock the silencer or controller for the tripper (not shown in the present drawings, but shown and described 105 in connection with Figure 7 of the aforesaid Letters Patent to Degener No. 1,271,290).

Under these conditions, with the parts arranged as shown in Figure 1, when not in 110 a computing zone, that is to say, when the cam 21 is not in engagement with the shifter or plunger 220, then the tripper (not shown) will be held in its raised position, and, even though it is vibrated by partial 115 depression of a numeral-key, the computing mechanism will be silent.

If it be desired to throw the computing mechanism out of action, even when it comes to a computing zone or column, the segments 229 and 230 may be manipulated by the finger 235, so that the spring 234, although thereby thrown to the other side of the lever 232, will still draw the lower arm of the lever 232 toward the segment 229, 120 but in the opposite direction, wherein the silencer or controller will be in its raised position, holding the tripper in ineffective 125 position.

If the arm 225 should be depressed at this 130

time under the action of the plunger 220, it would merely act idly against the spring 226, and there would be no tendency for the lever 232 to rock to such a position as to lower the tripper, because the spring 234 now acts in the opposite direction. The pin 228, which normally holds the segment against backward rotation, and, in fact, gives it a counter-rotation to aid the movement of the lever 232, will now be entirely clear of the lever 225, so that the lever 225 will have no tendency to swing the lever 232.

As shown in the patent to Degener No. 1,271,290, above referred to, certain safeguarding mechanisms are provided for preventing the actuation of the computing mechanism by the numeral-keys at inopportune times. A feature of this safeguarding mechanism is the locking thereby of the numeral-keys when writing in a denominational column corresponding to a comma between hundreds and thousands, etc., and to the decimal point. As to this locking of the numeral-keys, the mechanism is as follows.

Each numeral-key-lever 47 has connected thereto a link 48, the other end of which is connected to one arm of a bell-crank-lever 49; the other arm of which bell-crank-lever 49 has connected thereto a link or draw-rod 20. Depression of a numeral-key, therefore, in addition to swinging a type-bar in the usual manner, as, for instance, in the the Underwood standard typewriting machine, also effects movement of the draw-rod 20, to institute a number of operations or movements relating to the computing mechanism.

As more fully described in the Degener Patent No. 1,271,290, each draw-rod 20 (see Figure 16 of said Degener patent) has connected thereto a lever for effecting a setting of the pin-setting interponent, and each of such levers has an arm thereon, by means of which the movement of the lever, and, consequently, of the lever-key, may be blocked (see Figure 11 of said Degener patent), when a blocking device is interposed in the path of movement of such arm. This blocking device is in the form of a lever through an aperture in which the link 241 passes. The link 241, when the plunger 220 (see Figure 1) is operated by the cam 21, may move freely through the blocking device without moving the latter to effective position, and, therefore, without blocking movement of the numeral-keys. A more extensive movement of the link 241 may, however, be effected through the plunger 220, which will cause the blocking device to be thrown to effective position.

This more extensive movement of the link 241 causes a collar 253 thereon to engage and actuate the blocking device; and is effected by the cam-plate 19. For this pur-

pose, there are on the under edge of the cam-plate 19, and shown as spaced at three letter-space-distances apart, three tappets or teeth 50. These represent the positions for the commas and decimal point in the computing zone. The cam 21 at the end of the cam-bar 19, as heretofore mentioned, depresses the roller 22 on the top of the plunger to the level of the lower edge 51 of the cam-plate. The roller thereafter rides along the lower edge of the cam-plate and is held to the latter by the tension of the spring 226. On arriving at the first of the teeth 50, however, the plunger is given a further depression, and, in being thus so further depressed, acts in the same manner as before through its connections to the link 241, giving the latter link an additional thrust in the same direction as when thrust by the cam 21. This additional thrust causes the collar 253 on the link 241, by engagement with the blocking device, to actuate the latter, as stated. On passing the first of the teeth 50, the spring 226, by throwing the plunger to the edge 51 of the cam-plate, draws back the link 241 a distance sufficient to permit the blocking device to be thrown to ineffective position, and the numeral-keys to be operated. Upon engagement with the next and succeeding teeth 50, however, the blocking device is again operated to block the operation of the numeral-keys while the punctuation-mark is written.

The numeral-keys are automatically locked against operation upon movement of the carriage with the cam-piece 19 from a computing zone; and may or may not be maintained in such locked condition between computing zones. For effecting such locking of the numeral-keys, a cam 52, forming one edge of a tooth of greater length than the teeth 50, is provided on the end of the cam-plate opposite the cam 21. This cam 52 causes a depression of the plunger sufficient to permit a locking arm 53 to be swung by a spring 56 over the top of the plunger. The spring 56 is a coil-spring connected at one end to an ear 57 on the locking arm, and at its other end to an ear 58 on the fixed plate 28. Until the cam 52 depresses the plunger sufficiently to permit the locking arm 53 to pass thereover, the spring 56 merely causes the locking arm to bear against the side of the head of the plunger without interfering with the up and down movement of the latter. When the plunger or shifter 220 is depressed by the cam 52, the link 241 is thrown to the right a sufficient distance to cause the collar 253 thereon to act to block movement of the numeral-keys in the same manner as when the plunger or shifter is depressed by the teeth or cams 50, except that in this instance the collar 253 will continue to hold the numeral-key-blocking device in effective position until the plunger

or shifter 220 is released. The plunger or shifter when acted upon by the cam 52 has a greater movement than when acted upon by the teeth or cams 50, but this greater movement is not transmitted to the collar 253 in such manner as to cause the mechanism to be jammed at the blocking device, because of the flexible joint or connection provided by the spring 45. A locking down 10 of the plunger by the cam 52 has the further function of preventing vibration and rattling of the plunger by and over the teeth 50 upon return movement of the carriage.

In order that, in locking the plunger down 15 by the cam 52, it may not be disabled for operation by a cam 21 on a succeeding cam-plate 19, if any, such succeeding cam-plate, and, in fact, each cam-plate, has on its front face (see Figure 4) a tooth which is V-shaped to provide two cam-surfaces. As the cam-plate advances into the computing zone, the front cam-face 60 of the tooth 59 engages a pin 61 on the locking arm 53, thereby rocking the latter around its pivot 25 66 against the action of the spring 56, to clear the lock-arm from the plunger; whereupon the plunger rises under the action of the spring 226, to be free to respond to the action of the cam 21. On the return movement 30 of the carriage, the cam-plates pass over the plunger in the locked-down position of the latter until the cam-surface 63 on the other side of the tooth 59 acts upon the pin 61 to unlock the plunger. The ear 35 64 of the plate 28, which serves as a pivotal support for the locking plate 53, is provided with a stop-pin 65, to limit the throw of the locking plate under the action of its spring 56. Movement of the locking plate in the 40 other direction may be determined by the cam-plate 19, or by the rear face of the casting 30.

Although the numeral-keys are thus automatically locked as the cam-piece 19 leaves 45 the computing zone, they may be unlocked so that dates and other writings involving numerals may be written between column-zone positions. Such unlocking of the numeral-keys is effected by the means heretofore described for disabling the computing mechanism when the latter is not desired. This, it will be recalled, was done by throwing, to the right, the finger-piece 235 with the segment 230, so as to draw the link or rod 241 to the left. Therefore, although 50 the plunger or shifter 220 may continue to be held down by the locking plate 53, the collar 253 may, nevertheless, be withdrawn to the left to release the blocking device and numeral-key-levers for writing 55 between computing-zone positions. Such movement of the finger-piece 235 has no effect upon the lever 225 and connections therefrom to the plunger 220, because the 60 pin 228 on the segment 229 is at this time 65

swung away from the toe 227 through which it co-operates with the lever 225.

The column or computing zone stop 10^a, in addition to having combined therewith the cam-plate 19, also acts as the pick-up 70 for the computing-head carriage, that is to say, for the carriage, by means of which the master-wheel has its step-by-step movement through the computing head from higher to lower denominational columns or number-wheels, or by means of which similar movement of the computing head is effected with respect to the master-wheel. As hereinbefore stated, this pick-up mechanism may be of the kind shown in the United States 80 patent to Walter Wright, No. 1,244,398 of October 23, 1917, and so is not shown or described in the present application. In the present application, only the hook 55 itself, with its shoulder 62 thereon, for co-operation 85 with the jaw 11 of the stop 10^a, see Figure 6, is shown. For the manner in which the hook 55 is operated to be picked up and released from the stop 10^a, reference is made to the aforesaid Wright patent. 90

Variations may be resorted to within the scope of the invention, and portions of the improvements may be used without others.

Having thus described my invention, I claim:

1. In a typewriting and computing machine having a normally disabled computing mechanism; numeral key levers; a carriage movable in letter-feed and return directions; a cam or dog settable on the carriage in selected columns or computing-zone positions; means for setting the computing mechanism for operation thereof; and a plunger engageable by the cam or dog to operate said setting means when a computing zone is reached by movement of the carriage.

2. In a typewriting and computing machine having a normally disabled computing mechanism; numeral keys; a carriage 110 movable in letter-feed and return directions; means for setting the computing mechanism for operation thereof when a computing zone is reached by movement of the carriage and for setting the numeral 115 keys against operation at the punctuation positions of the carriage in the computing zone; a cam or dog on the carriage for initiating the action of the setting means for the computing mechanism; and another 120 cam or dog on the carriage for initiating the key-setting action.

3. In a typewriting and computing machine having a normally disabled computing mechanism; numeral keys; a carriage 125 movable in letter-feed and return directions; means for setting the computing mechanism for operation thereof when a computing zone is reached by movement of the carriage and for setting the numeral 130

- keys against operation at the punctuation positions of the carriage in the computing zone; a cam or dog on the carriage for initiating the action of the setting means for the computing mechanism; and another cam or dog on the carriage for initiating the key-setting action, said cams or dogs being settable as a unit in any selected computing-zone position.
4. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; and a column or computing-zone stop for the carriage, settable thereon in selected position, and forming, with said cams or dogs, a unitary structure.
5. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; and a plate settable in selected column or computing-zone position on the carriage and having said cams or dogs spaced thereon.
6. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; a plate settable in selected column or computing-zone position on the carriage and having said cams or dogs spaced thereon; and a column or computing-zone stop for the carriage having said cam plate unitary therewith.
7. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; a plate settable in selected column or computing-zone position on the carriage and having said cams or dogs spaced thereon; a column or computing-zone stop for the carriage having said cam plate unitary therewith; and means whereby said combined stop and cam plate may be secured to the carriage in any desired column or computing-zone position.
8. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; and a plate, attachable to the carriage, having thereon the cam or dog for setting the computing mechanism, and having the key-setting cams or dogs spaced at punctuation distances apart therealong.
9. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; and another cam or dog on the carriage for initiating the key-setting action; said setting means comprising a shifter engageable and variably movable by the cams or dogs for said several operations.
10. In a typewriting and computing machine having a normally disabled computing mechanism; numeral keys; a carriage movable in letter-feed and return directions; means for setting the computing mechanism

for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; said setting means comprising a shifter engageable by all of said cams or dogs, but movable by the key-setting cams or dogs a greater distance than by the cam or dog which sets the computing mechanism; and a lug or pick-up device effective only upon such greater movement of the shifter.

11. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action, said setting means comprising a shifter having a spring device for urging the same into the path of said cams or dogs; means for holding the shifter out of the path of the cams or dogs during return movement of the carriage; and means for releasing the shifter to action.

12. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action, said setting means comprising a shifter having a spring device for urging the same into the path of said cams and dogs; means for holding the shifter out of the path of the cams or dogs during return movement of the carriage; and a trip on the carriage for releasing the shifter to action.

13. In a typewriting and computing machine having a normally disabled computing mechanism; numeral keys; a carriage movable in letter-feed and return directions; means for setting the computing mechanism

for operation thereof when a computing zone is reached by movement of the carriage, and for setting the numeral keys against operation at the punctuation positions of the carriage in the computing zone; a cam or dog on the carriage for initiating the action of the setting means for the computing mechanism; another cam or dog on the carriage for initiating the key-setting action; said setting means comprising a shifter movable to an inoperative position out of the path of the cams or dogs; a detent for holding the shifter in such inoperative position; and a tooth on the carriage for disengaging the detent from the shifter preliminary to entry of the cams or dogs into the computing zone for the computing operation.

14. In a typewriting and computing machine; numeral keys; a carriage movable in letter-feed and return directions; means comprising a shifter for locking the numeral keys against operation at the punctuation positions of the carriage, in the computing zone; a cam-piece on the carriage having a cam for effecting the key-locking action of the shifter; and means for holding the shifter out of the path of the cam during movement of the carriage in return direction.

15. In a typewriting and computing machine; numeral keys; a carriage movable in letter-feed and return directions; means comprising a shifter for locking the numeral keys against operation at the punctuation positions of the carriage, in the computing zone; a cam-piece on the carriage having a cam for effecting the key-locking action of the shifter; means on the carriage for throwing the shifter to an ineffective position out of the path of the cam for movement of the carriage in return direction; a spring detent for holding the shifter in such ineffective position; and a detent on the carriage for moving the spring detent to release the shifter preliminary to entry of the cam into a computing zone in forward direction for a computing operation.

16. In a typewriting and computing machine; numeral keys; a carriage movable in letter-feed and return directions; means comprising a shifter for locking the numeral keys against operation at the punctuation positions of the carriage, in the computing zone; a cam-piece on the carriage having a cam for effecting the key-locking action of the shifter; a tooth or cam on the cam-piece for throwing the shifter to an ineffective position out of the path of the first-mentioned cam, for movement of the carriage in return direction; a spring detent for holding the shifter in such ineffective position; and a tooth on the cam-piece for disengaging said spring detent for the shifter preliminary to entry of the cam into a computing zone in forward direction for a computing operation.

nary to entry of the first-mentioned cam into the computing zone in forward direction, for a computing operation.

17. In a typewriting and computing machine; numeral keys; a carriage movable in letter-feed and return directions; means comprising a shifter for locking the numeral keys against operation at the punctuation positions of the carriage, in the computing zone; a cam-piece on the carriage having a cam for effecting the key-locking action of the shifter; a tooth or cam on the cam-piece for throwing the shifter to an ineffective position out of the path of the first-mentioned cam, for movement of the carriage in return direction; a detent pivotally mounted to be rocked into position to hold the shifter in its ineffective position; and a tooth on the cam-piece for rocking the detent out of holding engagement with the shifter preliminary to entry of the first-mentioned cam into the computing zone in forward direction, for a computing operation.

18. In a typewriting and computing machine; numeral keys; a carriage movable in letter-feed and return directions; means comprising a spring-pressed shifter for locking the numeral keys against operation at the punctuation positions of the carriage, in the computing zone; a cam-piece on the carriage having a cam for effecting the key-locking action of the shifter against the action of its spring; a tooth or cam on the cam-piece for throwing the shifter against the action of its spring to an ineffective position out of the path of the first-mentioned cam, for movement of the carriage in return direction; a detent pivotally mounted to be rocked into position to hold the shifter in its ineffective position; and a tooth on the cam-piece for rocking the detent out of holding engagement with the shifter preliminary to entry of the first-mentioned cam into the computing zone in forward direction, for a computing operation.

19. In a typewriting and computing machine; numeral keys; a carriage movable in letter-feed and return directions; means for locking the numeral keys against operation at the punctuation positions of the carriage in the computing zone, comprising connections having a limited throw; a shifter for actuating said connections; a cam or dog on the carriage for moving the shifter to effect the limited throw of said connections; means on the carriage for effecting a greater movement of the shifter to a position out of the path of said cam; and a flexible joint for the shifter to said connections to permit of such greater movement of the shifter without corresponding movement of said connections.

20. In a typewriting and computing machine; numeral keys; connections to the numeral keys for setting valuating devices

for the computing mechanism; means, having a limited throw, for disabling said setting connections; a carriage movable in letter-feed and return directions; a cam-piece attachable to the carriage; a shifter operable by the cam-piece for effecting the limited throw of the disabling means at the punctuation positions in the computing zone; means on the carriage for effecting a greater throw of the shifter to a position out of the path of said cam; and a flexible joint for the shifter to the disabling means to permit of such greater throw of the shifter without corresponding throw of the disabling means.

21. In a typewriting and computing machine having a normally disabled computing mechanism; numeral keys; a normally disabled connection to the numeral keys for setting the driving connections of the computing mechanism; connections to the numeral keys for setting valuating devices for the computing mechanism; a carriage movable in letter-feed and return directions; means for setting the key connection for drive of the computing mechanism, and for disabling the key connections to the valuating devices; comprising a shifter; a cam on the carriage for effecting one movement of the shifter to set the key connections for drive of the computing mechanism; and another cam on the carriage for effecting another movement of the shifter to disable the key connections to the valuating devices.

22. In a typewriting and computing machine having a normally disabled computing mechanism; numeral keys; a normally disabled connection to the numeral keys for setting the driving connections of the computing mechanism; connections to the numeral keys for setting valuating devices for the computing mechanism; a carriage movable in letter-feed and return directions; means for setting the key connection for drive of the computing mechanism, and for disabling the key connections to the valuating devices; comprising a shifter; a cam on the carriage for effecting one movement of the shifter to set the key connection for drive of the computing mechanism; another cam on the carriage for effecting another movement of the shifter to disable the key connections to the valuating devices; and a column or computing zone stop on the carriage having said cams unitary therewith for placement in selected column positions.

23. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys

- against operation except in the computing zone; a cam or dog on the carriage for initiating the action of the setting means for the computing mechanism; another cam or dog on the carriage for initiating the key-setting action; and a column or computing-zone stop for the carriage, settable thereon in selected position, and forming, with said cams or dogs, a unitary structure.
24. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation at the punctuation positions of the carriage in the computing zone, and except for operation in the computing zone; a cam or dog on the carriage for initiating the action of the setting means for the computing mechanism; other cams or dogs on the carriage for initiating the key-setting actions; and a column or computing-zone stop for the carriage, settable thereon in selected position, and forming, with said cams or dogs, a unitary structure.
25. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation except in the computing zone; a cam or dog on the carriage for initiating the action of the setting means for the computing mechanism; another cam or dog on the carriage for initiating the key-setting action, said setting means comprising a shifter engageable by all of said cams or dogs, but movable by the key-setting cams or dogs a greater distance than by the cam or dog which sets the computing mechanism; and a lug or pick-up device effective only upon such greater movement of the shifter.
26. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation except in the computing zone; a cam or dog on the carriage for initiating the action of the setting means for the computing mechanism; another cam or dog on the carriage for initiating the key-setting action, said setting means comprising a shifter having a spring device for urging the same into the path of said cams or dogs; means for holding the shifter out of

the path of the cams or dogs between computing zones; and means for releasing the shifter to action.

27. In a typewriting and computing machine having a normally disabled computing mechanism; numeral keys; a carriage movable in letter-feed and return directions; means for setting the computing mechanism for operation thereof when a computing zone is reached by movement of the carriage, and for setting the numeral keys against operation except in the computing zone; a cam or dog on the carriage for initiating the action of the setting means for the computing mechanism; another cam or dog on the carriage for initiating the key-setting action, said setting means comprising a shifter having a spring device for urging the same into the path of said cams or dogs; means for holding the shifter out of the path of the cams or dogs between computing zones; and manual means for releasing the shifter to action for writing between computing zones.

28. In a typewriting and computing machine; numeral keys; a carriage movable in letter-feed and return directions; means comprising a shifter for locking the numeral keys against operation except in the computing zone; a cam-piece on the carriage having a cam for effecting the key-locking action of the shifter; and means for holding the shifter out of the path of the cam during movement of the carriage between computing zones.

29. In a typewriting and computing machine, the combination with a platen-carriage, numeral-keys and computing mechanism, of a column or computing-zone stop on the platen-carriage, and means on the stop for causing the numeral-keys to be locked against operation between computing zones.

30. In a typewriting and computing machine, the combination with a platen-carriage, numeral-keys and computing mechanism, of a column or computing-zone stop on the platen-carriage, means on the stop for causing the numeral-keys to be locked against operation between computing zones, and manual means for releasing the numeral-keys for operation between computing zones.

31. The combination in a typewriting and computing machine having a platen-carriage, numeral-keys and normally disabled computing mechanism, of a column or computing-zone stop on the platen-carriage, and means on the stop for rendering operative the drive of the computing mechanism, when a computing zone is reached by a movement of the platen-carriage, and for locking the numeral-keys against operation between computing zones.

32. The combination in a typewriting and computing machine having a platen-car-

riage, numeral-keys and normally disabled computing mechanism, of a column or computing-zone stop on the platen-carriage, means on the stop for rendering operative the drive of the computing mechanism, when a computing zone is reached by a movement of the platen-carriage, and for locking the numeral-keys against operation between computing zones, and manual means for disabling the computing mechanism, and for releasing the numeral-keys for operation between computing-zone positions.

33. The combination in a typewriting and computing machine having a platen-carriage, numeral-keys and normally disabled computing mechanism, of a column or computing-zone stop on the platen-carriage, means on the stop for rendering operative the drive of the computing mechanism, when a computing zone is reached by a movement of the platen-carriage, and for locking the numeral-keys against operation between computing zones, and manual means connected to simultaneously set the drive for the computing mechanism, and release the numeral-keys for operation between computing zones.

34. In a typewriting and computing machine, the combination with a platen-carriage, numeral-keys and computing mechanism, of means on the platen-carriage for

rendering the numeral-keys inoperative between computing-zone positions.

35. In a typewriting and computing machine, the combination with a platen-carriage, numeral-keys and computing mechanism, of means on the platen-carriage for rendering the numeral-keys inoperative between computing-zone positions, and manual means for releasing the numeral-keys for operation between computing-zone positions.

36. In a typewriting and computing machine having a platen-carriage, and a device settable in selected column-position on the platen-carriage comprising a column or computing-zone stop, cams or dogs for locking the numeral-keys against operation, and a cam or dog for effecting an operative setting of a drive for the computing mechanism.

37. In a typewriting and computing machine having a platen-carriage, and a device settable in selected column-position on the platen-carriage comprising a column or computing-zone stop, means for locking the numeral-keys against operation between computing zones, and means for releasing the numeral-keys for operation in the computing zone.

OTTO THIEME.
